(57) **CLAIM**

The ornamental design for a weightlifting implement, as shown and described.

DESCRIPTION

FIG. 1 is a bottom, front, right perspective view of a weightlifting implement showing our new design;

FIG. 2 is a top, rear, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The uneven-length broken lines immediately adjacent to the shaded area define the bounds of the claimed design and form no part thereof. The even-length broken lines depicting the remainder of the weightlifting implement form no part of the claimed design.
